(57) **CLAIM**

The ornamental design for an oscilloscopy device, as shown and described.

DESCRIPTION

FIG. 1 is a first isometric view of an oscilloscopy device showing our new design;

FIG. 2 is a second isometric view of the an oscilloscopy device of FIG. 1;

FIG. 3 is a first side view of the an oscilloscopy device of FIG. 1;

FIG. 4 is a second side view of the an oscilloscopy device of FIG. 1;

FIG. 5 is a first end view of the an oscilloscopy device of FIG. 1;

FIG. 6 is a second end view of the an oscilloscopy device of FIG. 1;

FIG. 7 is a top view of the an oscilloscopy device of FIG. 1; and,

FIG. 8 is a bottom view of the an oscilloscopy device of FIG. 1.

The dash lines in the drawings depict portions of the oscilloscopy device that form no part of the claimed design. The dash-dot broken lines depict boundaries

1 Claim, 8 Drawing Sheets
